HYDRAULIC JACK

Joseph J. Mueller, St. Joseph, Mich., assignor to
 Auto Specialties Manufacturing Company,
 St. Joseph, Mich., a corporation of Michigan

Application December 12, 1942, Serial No. 468,768

3 Claims. (Cl. 254—93)

1

This invention relates to hydraulic jacks.

Among the objects of the present invention are to provide an hydraulic jack constructed so that the oil reservoir is cast integrally with the base of the jack thereby promoting simplicity and economy in manufacture and operation; to provide an hydraulic jack wherein the oil reservoir is cast integrally with the base of the jack and likewise forms a mounting for not only the high pressure pump cylinder, but also for the actuating mechanism which serves to operate the piston reciprocating in the high pressure pump cylinder; to provide an hydraulic jack wherein the oil reservoir is cast integrally with the base and wherein the pump cylinder is formed within and cast integrally with the oil reservoir whereby if there be any flaws in the metal castings of the pump cylinder the oil leaking therethrough will pass directly back into the oil reservoir and will not escape to the exterior walls of the jack; to provide an hydraulic jack wherein the pump cylinder is disposed vertically downwardly through the oil reservoir, being preferably cast integral therewith, and wherein the oil relief or by-pass valve mechanism is disposed directly in the oil reservoir whereby when the oil is released it passes directly into the reservoir and not through a series of tortuous restricted passages; to provide an hydraulic jack with a base provided with a cast hollowed out portion extending substantially one third of the way through the base whereby in the finish of the jack the necessity of drilling a substantial part of the base to form a passage for the ball valves is eliminated; to provide an hydraulic jack wherein the oil reservoir is cast integrally with the base which thereby gives added weight at the bottom of the jack, whereby to stabilize the same; to provide an hydraulic jack wherein the top of the outside malleable iron casting is provided with a plug inserted in a threaded fashion from the inside so that the internal pressure of the jack tends to seal and tighten this plug; to provide an hydraulic jack wherein the basal portion of the jack, including the liquid passages and the pump cylinder, are formed as an integral metal casting in a manner to eliminate the necessity of substantial machining of the parts; to provide an hydraulic jack with an oil reservoir and an internal passage leading therefrom to the ram, wherein the arrangement is such that when the jack is placed so as to be in operation with the ram in a horizontal position, the liquid will be drawn from the lowermost part of the reservoir to the ram; to provide these and other objects of invention, as

2

will be apparent from a perusal of the following specification when taken in connection with the accompanying drawings, wherein:

Figure 1 is a perspective view of the improved type of hydraulic jack.

Figure 2 is a vertical sectional view taken on the line 2—2 of Figure 1.

Figure 3 is a detailed sectional view taken on the line 3—3 of Figure 2.

Figure 4 is a fragmentary sectional view taken on the line 4—4 of Figure 3.

Figure 5 is a view showing the jack in horizontal position.

Referring now to the drawings in detail, the improved jack embodies a basal casting 2 which is provided centrally with an upstanding wall 4 providing a central well. The circular inner faces of the upstanding wall 4 are threaded as at 6, into which screws a stationary ram 8 having a central longitudinally disposed liquid passageway 10. An elongated hollow shiftable ram cylinder 12 formed of malleable iron encloses the ram 8. This ram cylinder 12 is provided with an inwardly extending shoulder 14 at its top, and the upper surface of the ram cylinder is suitably knurled or fashioned, as at 16, to grip the load to be lifted. The top of the ram cylinder 12 is provided with a screw threaded opening 18 into which is threaded the plug 20. This plug is provided with a head 22 on its inner end and with a hexagonal recess 24 in its outer or top end. The arrangement is such that the fluid pressure within the ram cylinder 12 tends to force the plug tightly to its seat to prevent leakage. At its outer end the stationary ram 8 is cut away as at 26 to receive a packing 28 between it and the inner wall of the ram cylinder 12. Likewise at the bottom, the ram cylinder is suitably threaded as at 30 to receive a packing 32 which lies between the bottom of the ram cylinder and the ram proper. At its outer bottom end the shiftable ram cylinder 12 is provided with a foot lift or step 34 which provides a second load receiving surface. The bottom of the ram 8 is recessed as at 36 and joins the internal passageway 10.

Cast integrally with the upstanding wall 4 of the base is an oil reservoir 38. This reservoir is preferably cylindrically shaped and is disposed laterally of the central axis or passageway 10 of the upstanding ram 8. The cylindrical reservoir extends substantially from one side of the base to the other, as indicated in Figures 1 and 3, and this reservoir is provided with a threaded opening at each end, such as 40 and 42, to receive threaded plugs 44 and 46 whereby to facilitate

the casting of the reservoir as well as to permit the filling of the same with suitable liquid, preferably oil. The plugs 44 are countersunk at their outer ends in a hexagonal manner to permit the removal and insertion of the same.

A high pressure pump cylinder is cast integral-
ly with the oil reservoir. As shown in Figures 2
and 3, the walls 48 are internally formed central-
ly of the reservoir, extending vertically down-
wardly as indicated in the above mentioned fig-
ures. At the top the pump cylinder cast-
ing 48 is shouldered as at 50 to receive a threaded
packing plug or ring 52 which serves to hold suit-
able packing 54 in position to prevent leakage out-
wardly around the pump piston. A pump piston
56 is adapted to be reciprocatingly mounted with-
in this cylinder 48 and to this end the pump pis-
ton is provided at its outer end with a cross bore
58 in which a pin 60 is disposed, and the pump
piston having at its inner or opposite end a
threaded shank to which is attached a nut 57
which supports a collar 59 being surrounded by
a leather pump washer 61, as shown in Figure 3.
The opposite ends of the pin 60 lie in registering
apertures 62 and 64 of ears 66 and 68 of an actu-
ator 70 pivoted as at 72 to the outer end of the
links 74 which are in turn pivoted by means of
the pin 76 to the ears 82 integrally cast on the top
surface of the reservoir 38. The actuator 70 is
provided with a socket 86 in which an operating
handle 88 may be inserted whereby upon recipro-
cation of the handle in a vertical plane the high
pressure pump will be actuated in a manner well
known in the hydraulic jack art to draw liquid
from within the interior of the reservoir 38
through the cast passageway 90 past the ball valve
92. This ball valve, as shown, is normally held by
means of a spring 94 on its seat 96. The liquid
will be drawn inwardly by an upward movement
of the piston 56 into the high pressure cylinder
39 and then upon downward movement of the pis-
ton 56 the ball 92 will be pressed against the seat
and the liquid will thence be transferred past the
larger ball 98, thence through the transversely
extending cast opening 100, thence through chan-
nel 102—104 into the recess 36 of the stationary
ram 8, thence up the longitudinal passageway 10
of the ram to cause the upward projection of the
shiftable ram cylinder 12. The ball valve 98 is
normally pressed to its seat by means of the
spring 99.

A diagonally disposed passageway 106 connects
the passageway 102 in the base of the jack with
the reservoir and the upper portion of this cross
passage 106 is provided with a valve seat 108
which is normally closed by means of a valve
formed on the inner end of a plunger 110 which
by means of the threads 112 engages correspond-
ing threads on a sleeve 114 cast integrally with
the inner walls 116 of the reservoir. Suitable
packing 118 held in position by means of a
threaded thimble 120 prevents leakage past this
plunger 110. Rotation of the outer end of the
handle 122 of this plunger opens communication
between the reservoir and the passageway 102 so
as to permit the passage of liquid directly from
the ram cylinder 12 back into the reservoir whereby
to release the pressure in the cylinder to permit
the descent or downward inward movement
of the ram cylinder relative to the ram 8 and the
base 2. It will be noted that by this arrangement
and by forming the passageway 106 directly within
the inner wall of the oil reservoir, leakage is
precluded since the oil in escaping must pass di-
rectly into the oil reservoir.

It will be noted that passage 102 is closed at
its outer end by a suitable threaded plug 103, and
it will be likewise noted that the passage 90 is
closed by another threaded plug 124, and in order
5 to give access to this plug the bottom portion of
the casting is hollowed out arcuately as at 126.

The front wall of the reservoir 38 is provided
with spaced outstanding ears 128 to which are
pivoted the opposite ends of a handle 130 for lift-
10 ing the jack at its base.

It will be noticed from Figures 3 and 5 that the
passageway 90 within the oil reservoir is arranged
so that the end 91 of this passageway terminates
15 relatively close to the vertical end wall 93 of the
oil reservoir, by which arrangement when the
jack is operated in the manner shown in Figure
5, that is to push horizontally, the end 91 is posi-
tioned relatively close to the wall 93 which now
20 becomes the bottom of the oil reservoir whereby
oil is drawn from the bottommost part of the res-
ervoir irrespective of whether the jack is oper-
ated from a vertical position or from a horizon-
tal position.

Obviously the invention is not limited to the
25 specific forms disclosed herein but is capable of
other modifications and changes without depart-
ing from the spirit and scope of the claims ap-
pended hereto.

Having thus described the invention, what I
30 claim as new and desire to secure by Letters
Patent is:

1. In an hydraulic jack in combination with a
basal casting having ram receiving walls, a ram
mounted in fluid-tight manner with respect to
35 a portion of said casting walls, a ram cylinder
surrounding said ram and shiftable relatively
thereto, said ram cylinder forming a load sup-
porting member, said basal casting having inte-
gral walls laterally of said ram forming a hollow
40 reservoir to contain liquid, an intermediate por-
tion of said reservoir having internal walls pro-
jecting downwardly through the reservoir and
providing a high pressure pump cylinder, a pis-
ton in said cylinder and an actuator for said pis-
45 ton, a wall of one of said cylinders being formed
with a bored portion forming a sleeve, the inner
end of said bored portion terminating within the
reservoir and the outer end of said bored portion
terminating outside of said reservoir, an elon-
50 gated adjusting means adjustably mounted in
said bored portion, packing means about the outer
end of said rod between it and the walls of the
reservoir, the inner end of said rod being formed
as a valve, said basal casting having passages
55 formed therein interconnecting the high pres-
sure cylinder and the space between the ram and
the ram cylinder, and likewise connecting with
the reservoir, said valve on said rod controlling
said last mentioned passage.

2. An hydraulic jack comprising a base having
substantially central upstanding walls forming a
well, a ram and a ram cylinder upstanding from
said base concentrically of the central axis of said
well, said base laterally of said well having hol-
60 low upstanding walls forming an elongated liquid
reservoir the central horizontal axis of which lies
transversely of the vertical axis of said ram and
ram cylinder, and the central part of said hori-
zontally disposed reservoir being opposite the cen-
tral axis of said ram cylinder, said reservoir at its
65 central part having internal hollow integral walls
forming a pump cylinder, a piston reciprocable in
said cylinder, one of the wall portions of said
pump cylinder having a hollow enlargement
70 forming a sleeve having its outer end open to the
75

exterior of said base and its inner end opening into said reservoir, a valve rod adjustably engaging within said sleeve and having a valve adjacent its inner end, the wall of said base within said reservoir being formed as a valve seat on which the valve normally seats, said base having liquid passages connecting said reservoir with said ram cylinder and with said pump cylinder and with said seat, one of said basal passages being formed in the base and lying substantially parallel with the bottom of the base with one end of said passage opening exteriorly of the base and the opposite end opening to said reservoir, said passage connecting with said ram cylinder thereabove, said passage having an additional conduit connecting therewith and with said pump cylinder, said passage having spaced valve seats disposed on opposite sides of said conduit, and spring actuated valves disposed in said passage to close upon said spaced seats.

3. An hydraulic jack comprising a base having a central well, a concentrically disposed and relatively shiftable ram and ram cylinder means mounted on said base and associated with said well, said base having a relatively flat bottom and said base having a substantially cylindrical elongated reservoir the walls of which are integral with said base, an end of said reservoir being flat and normal to the base and being disposed substantially adjacent the end wall of said base whereby said jack may be tipped so as to rest upon said flat end wall, the longitudinal axis of said reservoir extending transversely to the longitudinal vertical axis of said ram cylinder, the wall of said base beneath one end of said reservoir being hollow and opening outwardly and said opening being flush with the end of said base, that portion of the base which forms a continuation of said hollow portion of said base

being provided with an elongated liquid conduit extending parallel to the base, the substantially central portion of said reservoir opposite the longitudinal vertical axis of said ram cylinder being provided with integral walls forming a hollow sleeve the upper portion of which opens onto the outer portion of said reservoir and the inner portion of which sleeve connects with said elongated passageway, a piston reciprocating in said hollow sleeve, said hollow sleeve forming a high pressure pump cylinder, one of the wall portions of said hollow sleeve being enlarged and being formed as a second elongated hollow sleeve the longitudinal axis of which extends angularly to the longitudinal axis of the pump sleeve, the inner wall of said second sleeve having a threaded portion, the outer end of said second sleeve opening onto the outer end of said reservoir and the inner end of said second sleeve opening without in said reservoir, the wall of said base opposite and spaced from said second sleeve being formed as a valve seat, said base below said reservoir having a second elongated passage connecting with said first mentioned elongated passage, said second mentioned elongated passage connecting with the ram cylinder and with said valve seat in the reservoir, a threaded rod threading into said second mentioned sleeve, the inner end of said rod closing upon said valve seat, said first mentioned elongated passage having two spaced seats disposed on opposite sides of the conduit connecting said passage with the pump cylinder, spring actuated ball valves normally mounted on said seats, the inner terminus of said first mentioned elongated passage connecting with the bottom of the reservoir adjacent the flat end of said reservoir.

JOSEPH J. MUELLER.
